UNITED STATES PATENT OFFICE.

JAMES T. GREELEY, OF NASHUA, NEW HAMPSHIRE, ASSIGNOR TO GREELEY LABORATORIES, INCORPORATED, OF NEW YORK, N. Y., A CORPORATION OF NEW YORK.

HYPODERMIC SYRINGE.

1,236,426.

Specification of Letters Patent. Patented Aug. 14, 1917.

Application filed June 24, 1912. Serial No. 705,415.

To all whom it may concern:

Be it known that I, JAMES T. GREELEY, a resident of Nashua, in the county of Hillsboro and State of New Hampshire, have invented certain new and useful Improvements in Hypodermic Syringes, of which the following is a specification.

This invention has for its object to provide a hypodermic syringe comprising a liquid container and a hypodermic needle separably connected, the container being hermetically closed and charged with the liquid to be injected and the needle being adapted when applied to the container to penetrate a portion of the same and form an outlet through which the liquid may be ejected.

The invention consists in the improvements which I will now proceed to describe and claim.

Of the accompanying drawings:—

Figure 1 represents a longitudinal section of a hypodermic needle constituting one of the members of my improved syringe. Fig. 2 represents a partial longitudinal section and partial side elevation of the container constituting the other member of the syringe.

Fig. 3 represents a longitudinal section showing the container and syringe assembled, and in condition for operation, a part of the container being broken away.

Fig. 4 represents a section on line 4—4 of Fig. 2.

The drawing represents the parts considerably enlarged.

The same reference characters indicate the same parts in all the figures.

In the drawings:—12 represents a liquid container formed as a collapsible capsule, the material used being a suitable ductile metal or alloy such as is used for collapsible tubes to contain glue, paint and other materials. The inner end of the capsule is adapted to be closed in the usual or any suitable way after the capsule has been filled. The opposite or outer end of the capsule is provided with a reduced neck 13 adapted to enter the hub of a hypodermic needle and constituting a seat or coupling

part adapted to couple the needle hub to the container. As here shown, the neck 13 is considerably thicker than the collapsible wall of the capsule, the neck being therefore relatively rigid.

The outer end of the neck 13 is provided with an integral head 14 which hermetically closes the neck and is penetrable by the inner end of a needle, as hereinafter described.

16 represents a hypodermic needle having a penetrating outer end as usual and having also a penetrating inner end. To the needle, between its ends, is attached a hub 17 constituting a socket or coupling part adapted to receive the projecting portion of the neck 13 and to suitably engage the same to insure the retention of the needle in its operative relation to the container. As here shown, the neck 13 is externally screw threaded and the mouth of the hub 17 is internally screw threaded. The said parts of the neck and hub may, however, be formed to engage each other frictionally instead of positively. The pointed inner end of the needle projects a considerable distance into the interior of the hub, as shown by Figs. 1 and 3, the pointed inner end of the needle being at such distance from the attached end of the hub that when the parts are assembled, the inner end of the needle is caused to penetrate the head 14 and thus establish a communication between the interior of the container and the lumen of the needle, as shown by Fig. 3.

The hub 17 is preferably provided with a compressible washer 18 of rubber or other suitable material which is adapted to be compressed by the operation of assembling the needle and container, in such manner as to form a liquid tight joint around the inner end portion of the needle, as indicated by Fig. 3. Before the parts are assembled, the washer 18 is preferably partially penetrated by the inner end of the needle, as shown by Fig. 1, the washer occupying the outer portion of the interior of the hub. The entrance of the neck 13 into the hub displaces and compresses the washer which is forced against a tapering internal sur-

face portion 17^a of the hub, and is thus pressed inwardly against the periphery of the needle.

19 represents an annular rigid grip member which surrounds the base portion of the neck 13 and bears upon the breast portion 20 which connects the body with the neck of the container, and is adapted to receive the pressure of the thumb and 10 finger which holds the syringe while the charge is being ejected by the compression of the body of the container, the object of the grip member being to prevent the collapsing of the breast portion 15 of the container, as set forth in Letters Patent of the United States No. 1,021,146 dated March 26, 1912. The grip member 19 is distinguished from the grip member shown in said patent by the fact that its central 20 orifice has a wall 19^a formed to interlock with a seat 13^a on the neck 13 in such manner as to prevent rotation of the grip member 19 on the neck. As shown by Fig. 4, the inner wall 19^a and the seat 13^a are of 25 polygonal form and are fitted together friction tight so that a non-rotative engagement is established.

It will now be seen that the two parts or units of the syringe, namely, the container 30 and the needle, are adapted to be placed separately on the market, each container having the desired quantity of the solution to be injected and being hermetically closed so that there is no possibility of evaporation 35 or deterioration of the charge while it is kept in stock. An operative syringe may be quickly provided by assembling a container having the desired solution and a needle, the operation of assembling the parts insuring 40 a tight joint so that the liquid can escape from the container only through the needle.

Interposed between the members of the coupling is the compressible washer 18 which, as shown in Fig. 1, normally occupies 45 such position as to present a barrier that will prevent the needle 16 from accidentally puncturing the integral sealing head 14. The two members of the syringe may be connected and handled or shipped if desired 50 without liability of any accidental puncturing of the integral head 14, because the coupling members can not be interengaged to any great extent without considerable force being intentionally employed. The head 17 55 may be screwed far enough down upon the externally threaded neck 13 until the base of the washer 18 bears upon the flat upper face of the head 14, and the parts handled or shipped so connected.

60 When it is desired that the lower end of the needle shall penetrate the head 14, the hub 17 may be grasped by one hand and the grip member 19 by the other hand and then the two members can be relatively ro-

tated with sufficient force so that the washer 65 18 will be driven up toward and to the position indicated in Fig. 3, the last of this motion resulting in the end of the needle penetrating the head 14.

Before the parts are assembled as described, the washer 18 retains the position and condition shown in Fig. 1 so that it protects the needle and prevents access of any foreign matter to the inner end thereof, it being understood that the outer end of the 75 needle may be protected in any suitable way.

The capsule, its neck, and the neck closing head are formed from a single piece of ductile material. The relatively rigid neck 13 carries the head 14, introduces said head 80 into the needle hub, and holds the head in the path of the penetrating needle, which acts on the head after its entrance into the hub. It will be seen that there is no occasion for touching the head by the fingers at 85 any time either before or after the capsule has been filled. It is important that the outer surface of the head be kept in a sterile condition, because the penetrating instrument contacts with this surface before 90 breaking through the head, and might easily carry infection therefrom into the liquid in the capsule. The head supported by the neck as shown and described, and sterilized directly after the charging of the capsule, 95 may be readily kept sterile during its life, there being no liability, if the most ordinary care is observed, of rendering the head, unsterile.

I claim:

1. A hypodermic needle having penetrating outer and inner ends, and a hub secured between the said ends formed to surround the said inner end and to receive the neck of a liquid container, the hub being 105 provided internally with an unperforated compressible washer in which the inner end of the needle is embedded, said washer being adapted to be compressed around the inner end portion of the needle by the application of the hub to the neck of a liquid container.

2. A hypodermic needle having penetrating outer and inner ends, and a hub secured between the said ends formed to 115 surround the said inner end and to receive the neck of a liquid container, the hub being provided with a tapered internal surface and with an unperforated washer in which the inner end of the needle is embedded, said washer being adapted to be compressed between said surface and the needle by the application of the hub to the neck of a liquid container.

3. A hypodermic syringe member composed of a collapsible liquid container formed as a capsule and having a reduced integral neck having a threaded portion 125

adapted to engage an internally threaded needle hub and provided with a locking seat at its base portion and with a rigid annular grip member having an opening conforming to said seat whereby the neck may be forcibly screwed into such needle hub, the area of said grip member being such as to enable it to be grasped when screwing

the parts together without compressing the collapsible container.

10

In testimony whereof I have affixed my signature, in presence of two witnesses.

JAMES T. GREELEY.
